UNITED STATES PATENT OFFICE.

FITZ A. KIRBY AND JAMES HENNING, OF WYANDOTTE, MICHIGAN.

FLANGING-MACHINE.

SPECIFICATION forming part of Letters Patent No. 526,714, dated October 2, 1894.

Application filed October 2, 1893. Serial No. 486,940. (No model.)

To all whom it may concern:

Be it known that we, FITZ A. KIRBY and JAMES HENNING, citizens of the United States, residing at Wyandotte, county of Wayne, 5 State of Michigan, have invented certain new and useful Improvements in Flanging-Machines; and we declare the following to be a full, clear, and exact description of the invention, such as will enable others skilled in 10 the art to which it appertains to make and use the same, reference being had to the accompanying drawings, which form a part of this specification.

Our invention has for its object a cold plate 15 flanging and angle opening and closing machine, of superior construction and efficiency and it consists of the construction, combination and arrangement of devices and appliances hereinafter described and claimed, and 20 illustrated in the accompanying drawings, in which—

Figure 1 is a side elevation. Fig. 2 is an end elevation looking toward the flanging rolls on the left of Fig. 1. Fig. 3 is a view of 25 the opposite end. Fig. 4 is a plan view. Fig. 5 is a detail view in vertical section through the flanging rolls b^3 and b^7 on the shafts B' and B^2 . Fig. 6 is a detail view in vertical section through one of the nuts of one of the 30 screw shafts. Fig. 7 is a detail in vertical section through the bushing of the operating shaft, and adjacent bearing.

Our invention is especially adapted and designed to provide an improved flanging machine for flanging metal plates, used in ship-building, although we do not limit ourselves to any definite purpose to which the machine may be applied. It is well understood that in ship-building, metal plates are required 35 to be flanged in various ways and in various forms. Our invention contemplates a machine capable of straight plate flanging, also for forming flanges of hollow or rounding forms, and also by which a flange may be bent 40 at any desired angle, closing or opening at any desired bevel, and by which the angle can be varied, as desired, as the plate passes through the machine.

To these ends we carry out our invention, 45 as follows:

A denotes any suitable supporting frame which may be provided with stay-rods "a" extending longitudinally of the machine.

The frame is constructed with housings A' and A² in which are shown engaged lower rotatable shafts B and B', upon each of which is mounted a series of flanging rolls b, b', b², between the housings, and flanging rolls b³, on one extremity of each shaft outside the adjacent housing. The lower shafts are 55 shown immovable vertically. Above the shafts B, B' are located corresponding shafts B² and B³, each provided with corresponding flanging rolls b⁴, b⁵, b⁶ between the housings, and with a flanging roll b⁷ outside the housing, the latter corresponding to the flanging roll b³ there-beneath. One upper shaft with the lower shaft there-beneath, provided with the flanging rolls thereupon, form a set, two sets being shown, the one at the right hand 60 and the other at the left hand in Fig. 2. The upper and lower shafts are also provided, preferably, at their outer extremities opposite the flanging rolls b³ and b⁷, with straightening rolls b⁸ and b⁹.

C is a driving shaft which may be provided with a gear C', said gear meshing with gears B⁴ and B⁵ upon the two lower shafts B, B' respectively. The gear B⁵ meshes with a gear B⁶ on the corresponding upper shaft B³, and 70 the gear B⁴ meshes with a gear B⁷ on the corresponding upper shaft B². We do not, however, limit ourselves to any specific mechanism for driving the shafts with their flanging rolls.

The upper shafts B² and B³, with their flanging rolls, are shown as made vertically movable. To this end they are each provided with bearings A³ and A⁴, at the forward end, and with similar bearings at A⁵ and A⁶, at 75 their opposite ends, said bearings being vertically movable in suitable elongated orifices a', in the housing. Connected with each of these bearings is a screw threaded shaft D, D', D² and D³, respectively. These screw threaded shafts are provided toward their upper ends with corresponding nuts d, d', d² and d³, in which the corresponding screw threaded shafts work. With the nuts, are engaged corresponding adjusting gears E, E', 80

E^2 and E^3 , whereby they may be operated. To prevent the screw shafts from turning with the nuts, their upper ends may be formed with annular extremities, as shown at F , F' , 5 F^2 and F^3 .

G and G' denote wrenches, upon the extremities F , F' , F^2 , and F^3 , respectively, to hold the screw shafts from turning.

H denotes an adjusting shaft extending 10 longitudinally of the machine, provided with a worm gear toward each end, as shown at H' and H^2 , the worm H^2 in Fig. 1 being broken away to show the gear E^2 . The worm gear H' meshes with one of the adjusting gears on 15 the corresponding nut, which gears mesh one with the other. The worm gear H^2 meshes with one of the adjusting gears at the opposite end of the machine, which said gears also mesh the one with the other.

20 The operating shaft H may be provided with a hand wheel, or other suitable device preferably at each end thereof, as shown at H^3 . Obviously, the two screw shafts, at each 25 end of the machine, will be constructed the one with right hand and the other with left hand screw-threads. By this means the upper set of rolls may be readily adjusted vertically in a convenient and speedy manner.

It will be evident that by removing the 30 wrenches G , G' , the screw shafts can be properly adjusted in their corresponding nuts to suit the work, when the wrenches may be re-applied. By turning one of the hand-wheels H^3 , both of the upper sets of flanging 35 rolls may be vertically adjusted simultaneously. The left hand upper flanging roll, *i.e.*, roll b^7 on the shaft B^3 needs to be turned down a little lower than the corresponding upper roll in front thereof, in operation, to make 40 the two rolls each do their work successively. The work will be introduced to the flanging rolls b^8 , b^7 from the right hand of Fig. 2.

To throw the operating shaft H and its 45 worm gear out of mesh with the adjacent adjusting gears upon the nuts " d ," d' , d^2 , d^3 , the operating shaft may be provided with a bushing J within the bearing J' , of said shaft, the bushing being eccentrically connected with the operating shaft within the bearing. 50 It will be evident that by turning this bushing about on either end of the operating shaft, either or both corresponding worm gears will be thrown into or out of mesh with the corresponding adjusting gears. The 55 bushing may be operated for this purpose in any suitable manner. For example, the bearing J' may be constructed with an elongated arc-shaped slot j and the bushing be provided with a bar or lever j' passing through said 60 slot, whereby the bushing may be rotated, the ends of said slot limiting the rotation of said bushing.

For hollow and round flanging, the two left hand flanging rolls b^8 and b^7 , of Fig. 2, forming one set of rolls, should be loosely mounted 65

upon their corresponding shafts B' , B^8 , and 70 constructed to have a longitudinal play thereupon corresponding to the curve of the flange, as indicated in Fig. 5. For straight flanging, no longitudinal movement is required.

Our flanging machine, as above observed, is designed and adapted especially for flanging metal plate, cold. It is well understood 75 that the heating of such plates, to flange them, injures the plate, and that flanging them cold by hand, in the ordinary manner, is a very slow process. By our invention, however, the plates can be flanged cold in a very efficient and speedy manner. To get 80 the degree of flanging required, or the desired angle, it will be necessary to run the plate several times through the machine, tightening down the outer upper flanging rolls at each time the plates are run there-through.

85 Usually the plates will be marked on a line at which the flange is to be bent, and we design to provide the outer frame with an indicator finger Q to facilitate the guiding of the plate through the rolls on the line so marked.

It will be perceived that the V -rolls are on the lower shafts, as shown in the drawings, but the arrangement might be reversed within the scope of our invention. The flanging 95 rolls between the uprights of the frame are designed more particularly for shaping angle iron to required forms. While we have shown two sets of lower and upper shafts, with their flanging rolls, the machine would be operative with a single set of rolls, that is, a single lower shaft with a single upper shaft with their corresponding rolls.

It will be perceived that the V -shaped flanging rolls exert their pressure to effect 105 the desired flanging, on the line previously laid out, as above described, at the apex of the angle to be formed. For different thicknesses of plate it will be found desirable to substitute, upon the corresponding shafts, 110 flanging rolls of suitable form in order not to exert too severe a pressure upon the plate. The outer flanging rolls therefore can be made removable so that any desired form of roll may be applied upon the corresponding shaft 115 to suit the work required.

The threaded shafts D , D' , D^2 and D^3 are shown constructed with spherical heads at 120 their lower ends correspondingly seated in the bearings A^3 , A^4 , A^5 and A^6 . This forms a ball and socket joint at this point of construction. One set of flanging rolls is made V -shaped meshing with the corresponding rolls of inverted V -shape.

125 What we claim as our invention is—

1. A flanging machine having in combination a supporting frame, and a set of rotatable shafts provided at one of their extremities with corresponding flanging rolls b^8 and b^7 , one of said shafts made adjustable, and 130

said flanging rolls having a longitudinally reciprocatory movement upon said shafts, substantially as set forth.

2. A flanging machine having in combination

a supporting frame, a series of rotatable shafts provided at one of their extremities with flanging rolls b^3 and b^7 thereupon, and an additional series of rotatable shafts having corresponding flanging rolls thereupon, one series of said shafts made adjustable, and one set of flanging rolls having a longitudinally reciprocatory movement upon their corresponding shafts, substantially as set forth.

15 3. A flanging machine having in combination a supporting frame provided with housings, a lower set of rotatable shafts provided with flanging rolls at their extremities outside their housings, and an upper set of rotatable shafts provided with flanging rolls outside their housings and made adjustable, one set of flanging rolls having a longitudinally reciprocatory movement upon their corresponding shafts, substantially as set forth.

25 4. In a flanging machine, the combination of the supporting frame, the lower set of rotatable shafts provided with flanging rolls, and an upper set of rotatable shafts provided with flanging rolls and made vertically adjustable, one set of said flanging rolls being longitudinally movable on their corresponding shafts at one of their extremities provided with straightening rolls,—substantially as set forth.

35 5. In a flanging machine the combination of the supporting frame constructed with elongated orifices a' , a lower set of rotatable shafts provided with flanging rolls, an upper set of rotatable shafts provided with flanging rolls bearings for one set of shafts vertically adjustable in said elongated orifices in the frame, vertical threaded shafts connected with said bearings, means to prevent said vertical threaded shafts from turning, adjusting nuts engaging said threaded shafts, adjusting gears for adjusting said nuts, and an operating shaft geared with the adjusting gears, substantially as set forth.

6. In a flanging machine, the combination of the supporting frame, the lower set of rotatable shafts provided with flanging rolls, an upper set of rotatable shafts provided with flanging rolls, bearings in which the upper set of shafts are journaled, having a vertical movement in said frame, threaded shafts connected with said bearings, nuts engaging said threaded shafts, adjusting gears for adjusting said threaded shafts and an operating gear geared to the adjusting gears and means

for throwing said operating shaft out of engagement with the adjusting gears, substantially as set forth.

7. A flanging machine for cold plate flanging having in combination two sets of rotatable V-shaped rolls mounted upon their respective shafts and meshing with correspondingly grooved rotatable rolls, said rolls being adjustable vertically the one relative to the other, one of the said V-shaped rolls and its corresponding grooved roll having a longitudinally reciprocatory movement upon their respective shafts, substantially as set forth.

8. A flanging machine having in combination a supporting frame, a lower set of rotatable shafts provided with flanging rolls, an upper set of rotatable shafts provided with flanging rolls, bearings for one set of said shafts vertically adjustable in said frame, vertical threaded shafts having a jointed connection with said bearings, means to prevent the turning of said vertical threaded shafts, adjusting nuts engaging said threaded shafts, adjusting gear for adjusting said nuts, the shaft of the adjusting gear provided with a bearing J' , and a bushing J eccentrically connected to the shaft of the adjusting gear within said bearing, substantially as set forth.

9. A flanging machine having in combination a supporting frame, a series of rotatable shafts provided with flanging rolls, and additional series of rotatable shafts provided with flanging rolls, one series of said shafts made adjustable, and wrenches to hold the said shafts in adjusted position, substantially as set forth.

10. In a flanging machine the combination of a supporting frame provided with housings A' , A^2 , a lower set of rotatable shafts, each provided with flanging rolls located between said housings, and with a flanging roll at one extremity outside of said housings, an upper set of rotatable shafts each provided with flanging rolls located between said housings, and a flanging roll at one extremity outside the housings, and means for adjusting one set of said shafts, one of the upper and one of the lower flanging rolls upon the outer extremities of their respective shafts having a longitudinally reciprocatory movement thereupon, substantially as set forth.

In testimony whereof we sign this specification in the presence of two witnesses.

FITZ A. KIRBY.
JAMES HENNING.
